UNITED STATES PATENT OFFICE.

PATRICK GETHIN, OF CAMBRIDGE, MASSACHUSETTS.

TRUSS.

1,323,231.

Specification of Letters Patent. Patented Nov. 25, 1919.

Application filed June 27, 1918. Serial No. 242,159.

To all whom it may concern:

Be it known that I, PATRICK GETHIN, a citizen of the United States, residing at Cambridge, in the county of Middlesex, in the State of Massachusetts, have invented a certain new and useful Improvement in Trusses, of which the following is a specification, reference being had to the accompanying drawings.

10 This invention relates to trusses of the type commonly used for the relief of hernia, and my present purpose is to provide a truss, of simple and inexpensive construction, which may be used to support a plurality of ruptures and which may, at the same time, be utilized as a suspensory for the partial support of the scrotum, etc.

In order to explain my invention clearly I have provided the annexed drawing which 20 is a front face view, in elevation, of a truss embodying my present improvement.

In this drawing the letter *a* denotes the customary belt or strap by means of which the truss proper is secured in desired position on the body of the wearer, and in effective relation to the rupture or ruptures. The said truss, which is attached to the belt by means of loops *b*—*c*, as here shown, consists mainly of a single plate-like structure *d* 30 made of hard rubber, sole leather or the like sanitary material, which is slightly flexible. The said plate is extended downward and curved inward, as at *d'*—*d*² and thence further downward to provide an approximately semi-circular portion *d*³, the mid portion of 35 the said extension being cut away as at *e* to provide an opening of considerable size which is semi-circular at its lower portion.

The described construction provides an elongated plate portion of considerable length and width which may be utilized in some instances to support an abdominal rupture if no pads are used and it also provides side plate portions which may be utilized (either 40 one or both of said side portions) to support groin ruptures at the points *g*—*h* as indicated by dotted circles. When the truss is thus utilized the loop *d*³ lies underneath the scrotum and serves as a suspensory for said scrotum; the scrotum and penis projecting through the opening *e* and thus serving to prevent the lateral displacement of the truss.

Special pads may be located behind the described plate, in registering relation to each 45 rupture, if desired.

The plate *d* and the said pads as well, are preferably covered with chamois skin; the chamois skin presenting a somewhat roughened surface which prevents the accidental displacement of the pads after they have once been properly located between the plate 60 and the hernia. By thus leaving the pads free, they may be readily adjusted to any position within the capacity or limit of the plate *d*.

It will be seen that the plate includes an upper portion of suitable area to cover the lower portion of the abdomen, and curved so that its ends bear closely on the groins, and a lower portion of smaller area, having 65 a curved lower edge including reentrant curves, conforming to the inner surfaces of the legs of the wearer, and joining the ends of the upper portion, and a salient curve merging into the said reentrant curves, said 70 salient curve conforming to the lower portion of the opening *e*. The flexibility of the plate is such that, while the plate is adapted to conform approximately to the curvature of the abdomen, it is not 75 limp or flabby, and is adapted to confine and exert operative pressure on a pad or pads loosely and adjustably inserted between the plate and the body, the pressure being sufficient to retain the pad 80 or pads in any adjusted position according to the location of a rupture or ruptures. The relative stiffness of the plate enables the lower portion to be held in operative position by the upper portion of the plate and 85 by the attaching means, no straps extending between the legs of the wearer being required.

The preferred material of the plate is sole leather, this material being conformable to 90 the transverse curvature of the abdomen, and at the same time sufficiently stiff to enable the upper portion of the plate to hold a loosely inserted pad against the body without being locally bulged or displaced by the 95 pad, so that the plate is adapted to operatively press a pad against a ruptured portion of the body.

Having thus described my invention, I claim—

A truss plate composed of relatively stiff material, substantially such as hereinbefore specified, having an elongated upper portion provided with a body-encircling belt, and formed to extend across the abdomen 100 105 110 115

from groin to groin, the plate being conformable to the transverse curvature of the abdomen, and the end portions of the plate being adapted to enter the groin recesses, 5 and a reduced lower portion also relatively stiff, marginally shaped to conform to portions of the legs, and provided with an opening to receive a body member, whereby the plate may be anchored against vertical

displacement, the plate being sufficiently 10 stiff to enable its upper portion to hold a loosely inserted pad against the body without being locally bulged or displaced by the pad, so that the plate is adapted to operatively press a pad against a ruptured portion of the body. 15

PATRICK GETHIN.
